STORAGE RECEPTACLE AND BASE FOR ELEMENTARY ARITHMETIC INSTRUCTION SET

Charles E. Jones, Evanston, Robert H. Crowle, Mount Prospect, and William G. Crowle, Deerfield, Ill., assignors of one-half to Science Research Associates Inc., Chicago, Ill., a corporation of Delaware, and one-half to Western Publishing Company, Inc., Chicago, Ill., a corporation of Wisconsin

Filed Apr. 29, 1963, Ser. No. 74,645

Term of patent 14 years

(Cl. D25—1)

FIGURE 1 is an isometric view of a storage receptacle and base for elementary arithmetic instruction set showing the design;

FIGURE 2 is a side elevational view of the receptacle and base of FIGURE 1;

FIGURE 3 is a top plan view; and

FIGURE 4 is a front elevational view.

The broken line showing of counting members in FIGS. 2 and 4 is for illustrative purposes only.

We claim:

The ornamental design for a storage receptacle and

base for elementary arithmetic instruction set, as shown and described.
